United States Patent Office

Des. 196,338
Patented Sept. 17, 1963

196,338

STEREO VIEWER

Herman D. Post, Great Neck, N.Y., assignor to Robins
Industries Corp., Flushing, N.Y.

Filed July 12, 1962, Ser. No. 70,900

Term of patent 14 years

(Cl. D61—1)

FIG. 1

FIG. 2

FIG. 5

FIG. 3

FIG. 6

FIG. 7

FIG. 1 is a side view of a stereo viewer showing my new design;

FIG. 2 is a front view thereof;

FIG. 3 is a top view thereof on reduced scale and rotated at an angle of 180°;

FIG. 4 is a bottom view on reduced scale of the stereo viewer shown in FIG. 1;

FIG. 5 is a rear view thereof on reduced scale;

FIG. 6 is a cross sectional view taken along lines 6—6 of FIG. 1; and

FIG. 7 is a cross sectional view taken along lines 7—7 of FIG. 2. The side opposite to that visible in FIG. 1 is similar thereto.

I claim:

The ornamental design for a stereo viewer, as shown and described.
